(57) **CLAIM**

The ornamental design for a mobile device popup sleeve, as shown and described.

DESCRIPTION

FIG. 1 is a top plan view of a mobile device popup sleeve showing my new design in a not stretched position;

FIG. 2 is a bottom plan view of the mobile device popup sleeve of FIG. 1;

FIG. 3 is a right side elevational view of the mobile device popup sleeve of FIG. 1;

FIG. 4 is a left side elevational view of the mobile device popup sleeve of FIG. 1;

FIG. 5 is a front elevational view of the mobile device popup sleeve of FIG. 1;

FIG. 6 is a rear side elevational view of the mobile device popup sleeve of FIG. 1;

FIG. 7 is a perspective view of the mobile device popup sleeve of FIG. 1;

FIG. 8 is another perspective view of the mobile device popup sleeve of FIG. 1;

FIG. 9 is a perspective view of the mobile device popup sleeve of FIG. 1, wherein a sleeve opening of the mobile device popup sleeve is shown opened;

FIG. 10 is a top plan view of the mobile device popup sleeve of FIG. 1 shown in an alternate stretched position;

FIG. 11 is a bottom plan view of the mobile device popup sleeve of FIG. 1 shown in an alternate stretched position; and, FIG. 12 is a right side elevational view of the mobile device popup sleeve of FIG. 1 shown in an alternate stretched position.

The broken lines in the drawings depict stitching and are part of the claimed design.
